UNITED STATES PATENT OFFICE.

ROBERT C. PALMER, OF PENSACOLA, FLORIDA, ASSIGNOR, BY MESNE ASSIGNMENTS, TO THE GOVERNMENT OF THE UNITED STATES AND THE PEOPLE OF THE UNITED STATES.

METHOD OF DESTRUCTIVELY DISTILLING WOOD.

1,259,277

Specification of Letters Patent. Patented Mar. 12, 1918.

No Drawing.

Application filed March 23, 1917. Serial No. 157,059.

(DEDICATED TO THE PUBLIC.)

To all whom it may concern:

Be it known that I, ROBERT C. PALMER, a citizen of the United States of America, residing at Pensacola, in the county of Escambia, State of Florida, (whose post-office address is Pensacola, Florida,) have invented a new and useful Method of Destructively Distilling Wood.

The object of my invention is to treat 10 wood with a chemical which, when the wood is subsequently carbonized, will act as a catalyst and will cause more nearly theoretical yields of acetic acid and methyl alcohol.

It is well known that in the ordinary 15 method of carbonizing wood, such products as acetic acid and methyl alcohol are formed and may be recovered from the condensed vapors by suitable methods of refining and it is also known that the yield of these products is much less than the chemical analysis 20 of the wood indicates should be recovered.

It is also well known that if wood is heated in a boiling solution of a mineral acid, such as sulfuric acid or hydrochloric 25 acid, at a temperature much lower than the destructive distillation of wood, acetic acid will be formed but no methyl alcohol is produced by this means. The use of these acids at the temperature of the destructive distillation 30 of wood would not be practicable as the acids are either volatilized or oxidized and lost.

I have discovered that if wood is destructively distilled with an acid like phosphoric acid, which is non-volatile, at the 35 maximum temperatures used in the carbonization of wood, it is possible greatly to increase the amount of acetic acid and methyl alcohol formed from the wood as compared 40 to the usual methods of distillation.

In the practice of my invention the wood in any desired size or form is placed in a solution of orthophosphoric acid, pyrophosphoric acid, or metaphosphoric acid of any 45 desired or convenient strength, depending on the amount of acid it is desired to get into the wood, and the wood is then penetrated

by the acid by any of the means used for the penetration of wood by oils or other liquids, as employed in the preservation of wood 50 against decay. The amount of acid to be forced into the wood will vary with conditions, but may not exceed more than $2\frac{1}{2}$ per cent. of the dry weight of the wood. The wood is then removed from the solution and 55 the excess water may be evaporated, causing an increase in the strength of the acid. Following this operation, the wood is placed in any suitable retort and carbonized, either in the usual manner or by causing the vapors 60 arising from the wood to be confined, so that a pressure exists in the retort, preferably not exceeding 300 pounds per square inch. The vapors issuing from the retort are condensed and refined, in the usual manner, for the recovery 65 of the valuable products such as acetic acid and methyl alcohol. By this means the amount of acetic acid recovered may be as much as 14 per cent. of the weight of the wood, compared to a normal yield of 70 $4\frac{1}{2}$ per cent., and the amount of methyl alcohol recovered as much as $2\frac{1}{2}$ per cent. of the weight of the wood compared to a normal yield of 2 per cent.

Having thus described my invention, I 75 claim:

1. The process of treating wood with a solution of phosphoric acid by any means that will procure an intimate mixture of wood and acid and after evaporating any 80 excess water to place the wood in a suitable retort or carbonizing apparatus and destructively distill by applying heat to the retort in any manner that will attain a temperature sufficient to cause the formation of acetic 85 acid and methyl alcohol.

2. The process of treating wood with a solution of orthophosphoric acid to get an intimate mixture of wood and acid and heating the wood in a suitable retort to a temperature that will secure the maximum formation of acetic acid and methyl alcohol and confining the vaporous products arising from the wood until they are under a pressure not 90

2
exceeding 300 pounds per square inch, allowing the vapors to escape under pressure through a suitable outlet to a condenser where they are condensed and subsequently refined by any suitable means for the recovery of acetic acid, methyl alcohol or other valuable products.

In testimony whereof, I affix my signature in the presence of two subscribing witnesses.

ROBERT C. PALMER.

Witnesses:
